UNITED STATES PATENT OFFICE.

ANTONY T. SCARAMUZZI, OF PATERSON, NEW JERSEY, ASSIGNOR OF ONE-HALF TO
THOMAS J. CORRIGAN, OF PATERSON, NEW JERSEY.

SKEIN-DYEING MACHINE.

1,357,522.

Specification of Letters Patent.

Patented Nov. 2, 1920.

Application filed September 4, 1919. Serial No. 321,535.

To all whom it may concern:

Be it known that I, ANTONY T. SCARAMUZZI, a citizen of the United States, residing at Paterson, in the county of Passaic 5 and State of New Jersey, have invented certain new and useful Improvements in Skein-Dyeing Machines, of which the following is a specification.

This invention relates to that class of apparatus for treating skeins and the like in liquid baths, as in dyeing, for example, in which the skeins are hung on rods or equivalent carriers traversing the liquid vat, the carriers being adapted to be picked up and 15 shifted one after the other longitudinally of the vat (usually first in one direction and then the other), and also rotated, thus both to agitate the liquid of treatment and alter the position of the skeins on the carriers by 20 rotation of the skeins so that all of each skein will receive treatment. The invention consists in certain improvements in machines for doing this work automatically, the same being designed so as to require the 25 minimum of manual labor and of skill on the part of the attendants, to be simple in construction and reliable in operation.

In the drawings,

Figure 1 is a side elevation of the improved machine, a part of the near vat being broken away;

Fig. 2 is a horizontal sectional view on the line 2—2 of Fig. 1;

Fig. 3 is a right-hand end elevation; and 35 Fig. 4 shows the carrier in section on approximately the line 4—4, Fig. 2.

There are two inverted U-shaped yokes *a*, preferably suspended and adapted to be elevated as hereinafter explained, which 40 carry two horizontal, spaced and parallel rails *b* which form support for certain carriers to be described, and in the present example there are two vats *c* for the liquor of treatment arranged one on each side of 45 this support. The rails are notched, as at *d*, on their top surfaces at opposite points and regular intervals.

Each carrier comprises a bar *e* having a pair of spaced radial arms *f* on each end- 50 portion, and each pair of arms carries a bar *g* parallel with bar *e*, all three bars being in the same plane. Each carrier rests in a pair of the notches *d*, all the carriers being parallel and at the outset of each operation 55 all the notches are occupied by carriers

excepting a few at one end of the notched support *b*. The skeins are arranged on the ends of the carriers so as to embrace in each instance both bar *e* and a bar *g*, and it will be obvious that the double-bar form 60 of the ends of the carriers will effectually change the position of the skeins, which normally hang suspended in the liquid bath except when shifted and rotated in the way to be set forth, if the carrier be rotated on 65 its own axis.

Cross-pieces *h* of a pair of upright frames *i* afford journals for a pair of rotary worms *j* and an intermediate splined shaft *k*, one 70 of the worms and the shaft being connected by gearing *l*. There is further a pair of standards *m* in which is journaled a horizontal drive-shaft *n* which is connected by bevel gearing *o* with the two worms. This may be connected by a clutch *p* with an extension shaft *q*, journaled in the stand *r*, which carries a central idler pulley *s* and two fast pulleys *t* *t*; the clutch is controlled by the lever *s'* and the direction of rotation of shaft *q* may be controlled by any suitable 75 means for shifting a pair of suitably driven belts *v*, one of which is crossed, over the pulleys when it is desired to reverse the operation of the machine.

The carriage *w*, which is supported by the 80 worms, has its supporting legs *x* formed as nuts to engage the threading of the worms (Fig. 4), so that rotation of the worms effects advancement of the carriage longitudinally of the worms one way or the other, 85 according to the direction of rotation. The carriage has suitably arranged in it the intermeshing spiral gears *y*, *z*, the former of which is arranged on and engages the spline of shaft *k* (so as to rotate therewith but 90 slide thereon) and the latter of which has its axis formed by a shaft *2* (the journals for *z*—2 being preferably afforded by the up-standing sides *3* of the carriage). On the ends of the shaft *2*, which protrude from 95 said sides *3* of the carriage, are fixed radial arms *4* (which in the present instance are afforded by diametric arms both in the same diametric plane) the ends of which are widened to form hooks *5*. A half-gear *6*, 100 whose toothed periphery affords a way, sloping downwardly at each end, for the travel of the carriers over the carriage, is fixedly disposed at the inside of each side *3*; the said sides are curved in concentricity with 105 110

said ways, and it may be observed that the hooked ends of the arms 4 project somewhat beyond the peripheries of said sides, as shown in Fig. 4. The carriers have pinions 5 7 thereon which, when a carrier is picked up and moved over the carriage with the pinions in mesh with the toothed ways above referred to, cause the carrier to rotate on its own axis; the diameter of these pinions is 10 preferably such that the carrier will complete a turn, leaving its bar *g* below bar *e*, when it has traversed said way from one end to the other. The pinions, by engaging inwardly against the inner faces of 15 said sides 3, keep the carriers from shifting longitudinally and themselves thus in mesh with the toothed ways.

According to the direction of rotation of extension shaft *n* it will be apparent that 20 the carriage will travel one way or the other lengthwise of the worms, and when it has traversed its course in one direction by shifting the belts *v* it may be reversed. The gearing is such that the lifter formed by 25 *z*—2—4 rotates counter-clockwise when the carriage moves to the right (Fig. 4) and clockwise when the carriage moves to the left, and it is also such that the hooked ends of one or the other of a pair of arms 4 thereof are timed to coincide, or substantially so, with a pair of the notches *d* each time the arms pass upwardly through the plane in which the carriers are supported. 30 Therefore, as the carriage advances, the lifter, by its hooked ends, picks up the carriers, one after another, and raises each to the crest of the elevations, after which the carrier continues its progress due to the action of gravity and finally falls in the adjoining pair of notches behind the carriage, which by this time has advanced sufficiently 35 to expose them; the skeins on each carrier are by this operation not only lifted from one place in the vats and changed to another, but due to the gearing connecting each carrier with the carriage when it is passed over the same the carrier is rotated, so that the positions of the skeins thereon are 40 rotatively changed.

50 In order to facilitate the removal of the treated skeins and fitting others thereto the structure including the rails *b* and the yokes *a* may be elevated thus: In the uprights *i* is journaled a shaft 8 having a crank 9 on one end and a worm-wheel 10 on the other. Pitmen 11 connect eccentric points on the crank and worm wheel with vertical plungers 12 which slide in guides 13 on the uprights *i* and are rigidly connected to a 55 beam 14 which ties the two yokes *a* together. The worm-wheel 10 meshes with a worm 10' on shaft 15 journaled in one of the uprights *i* and having a sprocket and chain connection 16 with a counter shaft 17 also journaled 60 in said upright parallel with shaft *n*, said

shaft 17 having splined thereon a gear 18 which may be shifted by a lever 19 into or out of mesh with a gear 20 fixed on shaft *n*. When gear 18 is thrown into mesh with the rotating gear 20 (the connection between *n*—*q* being then disestablished) the structure *a*—*b*, with the carriers, will be elevated, and when elevated to the desired height the gear 18 may be shifted out of mesh with gear 20, said structure not being then free to fall 75 until its elevating train is again operated because of the worm and worm-wheel gearing 10—10'.

So far as I am aware it is not only new to change the positions of the skeins by the 80 means and in the manner herein set forth, and also to provide for their being elevated with reference to such means, but it is also new to provide a pair of spaced vats and place the means for changing the positions 85 of the skeins between them, whereby not only can a larger quantity of skeins be handled at a time but the operating mechanism leaves the vats clear at one side of each, so that the attendants can readily have access 90 thereto. So far as I am aware it is also new to provide a skein carrier of substantially the form herein set forth, to wit, elongated and with its intermediate portion forming a journal and its end portions each transversely widened so as to effect rotative 95 change of position of the skeins thereon when the carrier is rotated.

Having thus fully described my invention, what I claim as new and desire to secure by 100 Letters Patent is:—

1. In a skein dyeing machine or the like, the combination, with a set of elongated skein carriers arranged parallel and substantially horizontal, a substantially horizontal support on which the carriers rest, a carriage movable substantially horizontally from one end to the other of the set of carriers and having a surface forming a way for travel in contact therewith of the carriers backwardly past and over the advancing carriage, and means in the advance of the carriage to move said carriers successively from the position of rest of each forward of the carriage over the latter in contact with said 110 way to a position of rest on said support back of the carriage.

2. In a skein dyeing machine or the like, the combination, with a set of skein carriers arranged parallel and substantially horizontal, a substantially horizontal support on which the carriers rest, a carriage movable substantially horizontally from one end to the other of the set of carriers and having a rising and falling surface affording a way 125 for travel in contact therewith of the carriers backwardly past and over the advancing carriage, and means in the advance of the carriage to move said carriers successively from the position of rest of each for- 130

ward of the carriage over the latter in contact with said way to a position of rest on said support back of the carriage.

3. In a skein dyeing machine or the like, 5 the combination, with a set of elongated skein carriers arranged parallel and substantially horizontal, a substantially horizontal support on which the carriers rest, a carriage movable substantially horizontally 10 from one end to the other of the set of carriers and having a surface forming a way for travel in contact therewith of the carriers backwardly past and over the advancing carriage, and means in the advance of 15 the carriage to move said carriers successively from the position of rest of each forward of the carriage over the latter in contact with said way to a position of rest on said support back of the carriage, said carriage 20 and each carrier having coacting means to cause the carriers to rotate while traveling over said way.

4. In a skein dyeing machine or the like, 25 the combination, with a set of elongated skein carriers arranged parallel and substantially horizontal, a substantially horizontal support on which the carriers rest, a carriage movable substantially horizontally from one end to the other of the set of carriers and

having a progressively toothed surface forming a way for travel in contact therewith of the carriers backwardly past and over the advancing carriage, said carriers each having a peripherally toothed member alined and adapted to mesh with said toothed way, 35 and means in the advance of the carriage to move said carriers successively from the position of rest of each forward of the carriage over the latter with its said member in mesh with said way to a position of rest on said support back of the carriage. 40

5. In a skein dyeing machine or the like, the combination, with a set of elongated skein carriers arranged parallel and substantially horizontal, a substantially horizontal 45 support on which the carriers rest, and means to pick up the carriers and move them one after another to another position of rest on the support, including a carriage movable from one end to the other of the set of carriers, a horizontal shaft journaled in the carriage and a radial carrier lifting arm fixed on the shaft, said carriage having concentric with said shaft an elevated surface upon which the lifted carriers travel over 50 the carriage. 55

In testimony whereof I affix my signature.

ANTONY T. SCARAMUZZI.
